COMBINATION SCRAPER AND SQUEEGEE FOR CLEANING WINDSHIELDS

Anne Doster, Toronto, Ontario, Canada, assignor to
Woodbridge Moulded Products Limited, Toronto,
Ontario, Canada, a corporation of Canada

Filed June 12, 1963, Ser. No. 75,321

Term of patent 3½ years

(Cl. D9—6)

FIG. 1

FIG. 3

FIG. 4

FIG. 2

FIG. 1 is a top plan view of a combination scraper and squeegee for cleaning windshields, showing my new design;

FIG. 2 is a side elevational view thereof;

FIG. 3 is a bottom plan view thereof; and

FIG. 4 is an elevational view thereof taken from the opposite side to that shown in FIG. 2.

The broken lines shown in FIG. 2 are for illustrative purposes only.

I claim:

The ornamental design for a combination scraper and squeegee for cleaning windshields, as shown and described.
